UNITED STATES PATENT OFFICE

RALPH E. THOMPSON, OF BROOKLINE, MASSACHUSETTS, ASSIGNOR TO GILLETTE SAFETY RAZOR COMPANY, OF BOSTON, MASSACHUSETTS, A CORPORATION OF DELAWARE

SAFETY RAZOR

Application filed July 2, 1929. Serial No. 375,539.

This invention relates to safety razors of the type wherein a cap and guard holder is employed to position a replaceable blade at substantially right angles to the handle of 5 the razor.

I have discovered that the capacity of such a safety razor is increased, that it is adapted for certain special uses and that its shaving efficiency is improved by providing a series 10 of spaced connecting devices formed in the holder which may be employed selectively in attaching the handle thereto. Certain of these advantages are, moreover, secured by providing a connecting device located near one 15 end of the holder or adjacent to the end of the cutting edge of the blade; for example, when the handle is connected to the holder at a point near one end of the blade it tends in use to impart an oblique shaving position to 20 the blade. This is partly because the pull of the blade upon the handle is to some extent unbalanced so that the razor as a whole tends to swing slightly toward a position in which the blade is oblique to the line of 25 movement of the razor as a whole.

Another advantage of a razor organized in this manner is that substantially the entire length of the blade may, if desired, be located between the handle of the razor and 30 the eye of the user. This facilitates securing a straight and properly located line at the edge of the hair in front of the user's ears. Similarly the narrow portion of the blade near the end thereof and directly opposite the handle is under more immediate 35 and perfect control of the user than heretofore and may be used with an improved degree of accuracy.

While the advantages above discussed are 40 derived primarily from locating a connecting device for the handle adjacent to one end of the holder, a series of spaced connecting devices, including one located substantially 45 symmetrically in the holder, afford the user a wide range of choice in the character and adjustment of his razor during the shaving operation. For example, he may prefer to employ the razor with the handle symmetrically disposed for shaving the first time over 50 his face and then change to an unsymmetric-

cal disposition of the handle for the second time over and for accurate trimming of different parts of his face.

These and other features of the invention will be best understood and appreciated from 55 the following description of a preferred embodiment thereof selected for purposes of illustration and shown in the accompanying drawing, in which

Fig. 1 is a view in perspective of a safety 60 razor showing the handle connected at a point adjacent to one end of the holder.

Fig. 2 is a view in perspective of the cap.

Fig. 3 is a view in perspective on a reduced scale showing the razor in Fig. 1 in 65 use, and

Fig. 4 is a diagrammatic view indicating the tendency of the razor to advance the blade obliquely in the shaving operation.

My invention is herein illustrated as embodied in a safety razor of well-known type although it is not limited to that or to any specific form of razor.

The holder comprises a cap member 10 having a convex outer surface and a concave 75 inner blade-shaping surface. The cap is provided with two threaded studs of substantially equal length which project in parallel relation from the blade-shaping surface of the cap. The stud 14 is located in the cap 80 substantially symmetrically; that is to say, half way between its end and intersecting its longitudinal axis. The stud 12 is located centrally of the cap adjacent to one end.

The guard member 16 corresponds substantially in length to the cap 10 and is provided with a pair of longitudinally extending shoulders 17 over which the edges of the blade are bent when the razor is assembled. It is provided with guard teeth along either edge 90 and with perforations for the passage of the threaded studs 12 and 14.

The blade 20 is of thin flexible steel sharpened at both edges and provided with apertures adapted to register with and receive the 95 studs 12 and 14. The handle 18 is internally threaded at its lower end and may be connected to the holder by threaded engagement with either of the studs 12 or 14. As shown in the accompanying drawing it is connected 100

to the stud 12, and accordingly located adjacent to the left-hand end of the blade 20. By disengaging the handle 18 from the stud 12 and connecting it to the stud 14 a razor of the well-known symmetrical and balanced type is secured.

10 By connecting the handle to the stud 12 an unbalanced construction is secured, graphically represented in Fig. 4. In this figure the broken line 22 indicates the initial position of the handle and the broken line 24 the initial position of the blade. The arrows 26 indicate the theoretical uniformly distributed frictional and shaving resistance to the movement of the blade in a direction perpendicular to its edge. The center of this effect is represented by the arrow 30. It will be apparent, therefore, that the resultant of this force tends to swing the razor as a whole in the position indicated in Fig. 4 by full lines whenever an attempt is made to move the razor in a direction perpendicular to its cutting edge. The result is an oblique disposition of the blade with reference to its line of movement, which is the most favorable condition for an efficient shaving cut.

Having thus described my invention what I claim as new and desire to secure by Letters Patent is:—

- 30 1. A safety razor comprising an elongated holder, a blade positioned therein, a handle disposed at an angle to the holder, and means presenting a series of spaced parallel threaded stems constructed and arranged to be selectively engaged by the handle.

35 2. A safety razor comprising a cap and guard holder having a blade positioned therein, a handle disposed at an angle to the blade, and means presenting separate threaded stems arranged in parallel relation and located at different positions along the axis of the blade to be selectively engaged by the handle.

40 3. A safety razor comprising a cap and guard holder having a blade positioned therein, a handle disposed at right angles to the blade, and separate threaded stems arranged in parallel relation on the holder and located at different points in its length which may be selectively engaged by the handle.

45 4. A safety razor comprising a cap and a guard shaped to clamp a flexible blade between them, the cap having threaded stems projecting in parallel relation through openings in the guard, one of said stems being located at the center of the cap and the other being located near one end thereof, and a handle arranged to be connected to either stem as desired.

50 5. A safety razor comprising a cap and a guard shaped to clamp a flexible blade between them, the cap having threaded stems projecting in parallel relation through openings in the guard, one of said stems being located at the center of the cap and the other being located near one end thereof, and a handle arranged to be connected to either stem as desired.

55 6. Signed at Boston, Massachusetts, this first day of July, 1929.
